UNITED STATES PATENT OFFICE.

FREDERICK B. LEOPOLD, OF EVANSTON, ILLINOIS.

FILTER-TABLE.

No. 829,021.

Specification of Letters Patent.

Patented Aug. 21, 1906.

Application filed October 27, 1905. Serial No. 284,731.

To all whom it may concern:

Be it known that I, FREDERICK B. LEOPOLD, a resident of Evanston, in the county of Cook and State of Illinois, have invented 5 a new and useful Improvement in Filter-Tables; and I do hereby declare the following to be a full, clear, and exact description thereof.

My invention relates to sample-tables for 10 filter plants, its object being to provide suitable apparatus by means of which samples of the filtered water from different filters, the raw water, or treated water may be conducted to a common point and separately 15 exposed side by side to the view of the operator for the purposes of comparison or test at any time during the operation of the plant.

To these ends my invention comprises, 20 generally stated, a suitable table or platform having a series of transparent cylindrical or other shaped receptacles with connections thereto from the various filters, the raw-water supply, &c., and means for delivering the water to said receptacles, whereby the condition of the different samples of water will 25 be visible to the eye of the operator at all times during the operation of the plant.

To enable others skilled in the art to make 30 and use my invention, I will describe the same more fully, referring to the accompanying drawings, in which—

Figure 1 is an end view of my improved sample-table and connections leading to the lifting apparatus. Fig. 2 is a plan view 35 thereof. Fig. 3 is an enlarged sectional view on the line 3 3, Fig. 2. Fig. 4 is an enlarged view of one of the water-receptacles, partly in section; and Fig. 5 is a cross-section on the line 5 5, Fig. 4.

40 Located within the filter building is the table 2, which may be of any suitable construction, that shown being formed of wood with paneled ends and sides. Mounted on the table 2 are a series of transparent cylinders 3, said cylinders being held between the base-rings 4 and the caps 5. Interposed between the upper and lower ends of the cylinders and the base-pieces 4 and caps 5 are the rubber or other gaskets 6, the parts of the 45 cylinder being securely held together by means of the tie-bolts 7, which pass through the cap-pieces 5 and through the base-pieces 4 to the top 8 of the table 2, said tie-bolts being provided with the nuts 9 at the lower ends 50 thereof. By this construction the cylinders may be readily removed and taken apart for

the purpose of cleaning or for the renewal of the gaskets 6 when necessary.

The table-top 8 may be formed of marble or other suitable material provided with the 6c openings 10, through which pass the pipes 11, leading to the corresponding cylinders. The upper ends of the pipes 11 are threaded and screwed into the threaded openings 12 in the base-pieces 4. The gooseneck 13 is threaded 65 into an opening in the cap-piece 5, said gooseneck being provided with the valve 14 and the outlet 15.

The pipes 11, leading to the several cylinders, are connected up with suitable pumps 70 or lifters 16, located down in the pipe-galleries below the floor 17 of the building, said pumps being operated by independent motors or as a multiple pump operated by either water or electric motor. Each of the 75 pumps 16 is provided with an inlet-pipe 18, which leads directly from the point from which it is desired to convey samples to the glass cylinders. Accordingly each of the pipes 18 is connected up with the discharge-pipes 18^a, which carry off the filtered water from suitable filter-beds 18^b. These pipes 18 tap the pipes 18^a just before they connect with the main pipe 18^c. Each pump is furthermore provided with an outlet-pipe 19, 80 which conducts the water passing through said pumps directly to the cylinder.

In order to properly designate each cylinder and its source of supply, brass plates 20, 85 are secured to the table-top 8 at points opposite each cylinder, said plates bearing the 90 number of the filter from which the water is conducted to the cylinder. In the drawings we have illustrated the table as having six 95 cylinders connected up with corresponding filter-beds, the ends cylinders being connected directly with the raw and treated water supply as supplied by the pipes 26 and 27.

Located in openings 28 in the table-top 8 100 are the funnels 29, which coincide with the outlets 15 of the goosenecks 13, so that the water discharged from said goosenecks will pass into said funnels. These funnels 29 are connected up with the pipes 30, which 105 convey the water to the waste.

When my improved sample-table is in operation and it is desired to test or make comparison of the waters from the different filters, the motors operating the pump 16 are 110 put into operation, whereupon the water from the six filter-beds will be conducted up

into their respective cylinders 3, whereupon the condition of the water from the several filters is always visible to the eye of the operator of the plant and he is thus able to readily determine whether the filter-beds are working uniformly or whether any of them are not working up to the proper point of efficiency. Furthermore, by turning suitable valves he is able to conduct the raw or treated water by means of the pipes 26 and 27 to their respective cylinders, so as to compare their condition with that of the filtered water. The waters may be held in the cylinders 3 by closing the valves 14 in the goosenecks 13, or the water may flow continuously through the cylinders 3 by opening the valves 14, whereupon the water is discharged into the funnels 29 and carried off. The name-plates 25 designate the source of supply to the different cylinders, and the operator has always before him the waters particularly designated, so that there is no opportunity for mistakes. It is of course apparent that by the use of independent motors for operating the pump 16 the water may be selected from any desired filter without the necessity of working all the cylinders of the table at one time.

By my improvement I provide a very convenient and simple form of sample-table by means of which the waters are always visible to the eye of the operator for purposes of comparison and the necessity of an operator climbing down into the congested pipe-galleries for the purpose of viewing the condition of the water is avoided, and it has been found in practice that owing to this inconvenience the tendency of the operator was to neglect this duty of inspection.

By the use of the gooseneck connection it is possible to obtain samples of the waters for analysis, if desired.

What I claim is—

1. Apparatus of the character described, comprising a suitable table, or platform, a

series of transparent receptacles thereon, and connections from different filter-beds, the raw-water supply, &c., to said receptacles.

2. Apparatus of the character described comprising a suitable table, or platform, a series of transparent receptacles thereon, connections from different filter-beds to said receptacles, and means for forcing the water into said receptacles. 50

3. Apparatus of the character described comprising a suitable table, or platform, a series of transparent receptacles thereon, connections from different sources of water-supply to said receptacles, and means for carrying away the contents from said receptacles. 55

4. Apparatus of the character described comprising a suitable table, or platform, a series of transparent receptacles thereon, connections from different filter-beds to said receptacles, and a series of pumps or water-lifters to force the water up into said receptacles. 60

5. Apparatus of the character described comprising a suitable table, or platform, a series of transparent receptacles thereon, connections from different sources of water-supply to said receptacles, outlet connections leading from said receptacles, and drain-pipes in said table in line with said outlet connections. 70

6. Apparatus of the character described comprising a suitable table, or platform, a series of transparent receptacles thereon, connections from different sources of water-supply leading to said receptacles, and name-plates on said table designating the source of supply and located opposite each receptacle. 80

In testimony whereof I, the said FREDERICK B. LEOPOLD, have hereunto set my hand. 85

FREDERICK B. LEOPOLD.
